US00D756363S

(12) **United States Design Patent**
Mathis et al.

(10) **Patent No.:** US D756,363 S
(45) **Date of Patent:** ** May 17, 2016

(54) **DISPLAY FOR USE WITH PEN-TYPE
INJECTION DEVICE**

(71) Applicant: **Sanofi-Aventis Deutschland GmbH**,
Frankfurt am Main (DE)

(72) Inventors: **Jan Mathis**, Vienna (AT); **Nik Pelzl**,
Vienna (AT)

(73) Assignee: **SANOFI-AVENTIS DEUTSCHLAND
GMBH**, Frankfurt am Main (DE)

(**) Term: **15 Years**

(21) Appl. No.: **29/536,761**

(22) Filed: **Aug. 19, 2015**
